ALBERT F. ANDERSON AND CHARLES W. ARMSTRONG, OF TACOMA, WASHINGTON.

ELECTRIC-LIGHT BRACKET.

1,025,442.

Specification of Letters Patent.

Patented May 7, 1912.

Application filed February 9, 1911, Serial No. 607,551. Renewed December 18, 1911. Serial No. 666,612.

To all whom it may concern:

Be it known that we, ALBERT F. ANDERSON and CHARLES W. ARMSTRONG, citizens of the United States, residing at Tacoma, in the county of Pierce and State of Washington, have invented a new and useful Electric-Light Bracket, of which the following is a specification.

This invention relates to brackets for electric lights and has for its objects to provide an adjustable support for the light, by means of which the light can be placed in a great variety of positions, and such that the light having been thus placed it will remain in said position until moved again. We attain these and other objects by the devices, mechanisms, and arrangements illustrated in the accompanying drawing in which—

Figure 1 is a side view showing the bracket extended horizontally from the wall; Fig. 2 shows the same bracket folded and swung against the wall; Fig. 3 is a section showing the spring clamp; and Fig. 4 is a diagrammatic view showing the bracket 25 in two extended positions to illustrate the adjustment thereof.

Similar numerals of reference refer to similar parts throughout the several views.

This bracket is adapted to turn about a vertical axis, and its end on which the electric light is carried is adapted to occupy any position radially between the inner and outer limits thereof and any vertical position within a great area.

Referring now to the drawings, the plate 1 is secured to the wall or other support by any suitable means. The four screws 2 are arranged in pairs along a vertical line, each pair passing through the eyes formed in the 35 ends of suitable yoke pieces 3, said yoke pieces being raised from the surface of the plate 1 by suitable washers 4. The yoke pieces 3 are cylindrical between the eyes formed in their ends and may suitably be 40 made of heavy wire. These yoke pieces form the pintles about which the bracket swings. Around each yoke piece 3 a metal strip 5 is passed to form the hinge of the bracket. To one of these strips 5 is pivotally secured a bar 6, while a similar pair of bars 7 are similarly secured to the other strip 5, one of said bars 7 passing on each side of the bar 6 where they cross. All of the bars 6 and 7 are provided with similar elongated 55 slots 8 extending practically their full lengths. The other ends of the bars 6 and 7

are each pivotally secured to the ends of two equal bars 9 which are pivotally joined in their centers, and which are in turn pivotally secured at their other ends to other similar bars 9, all said bars 9 acting together to form an extensible bracket. A screw-adjusted spring clamp passes through the slots 8 in the bars 6 and 7 and holds their outer ends in whatever position they may be placed in. This clamp consists of a bolt 10 passing through the slots 8 and engaging one of the bars 7 by its head 11 and having a thumb-nut 12 at its other end and a washer 13 between the thumb-nut and the other bar 7. A spring 14 is wound around the bolt 10 between the thumb-nut 12 and the washer 13 and is adapted to be compressed by the thumb-nut and to press the bar 6 tightly between the two bars 7, thus holding them all 75 in the adjusted position and yet allowing them to be moved therefrom whenever desired without touching the thumb-nut. If, however, the bars 6 and 7 tend to slip out of the said adjusted position, the thumb-nut 80 may be tightened until the friction therebetween is sufficient to hold them. A goose neck 15 is pivotally attached to the ends of the end bars 16 of the bracket, said end bars 16 being only one-half as long as the bars 9, 85 by means of a spring clamp similar to the clamp above described. We prefer to form the pivots of the bars forming the bracket hollow, as shown in the drawings, and in this case the electric cord 17 passes through 90 the upper pivot joining the bars 7 to the first bar 9 and then down the said bar 9 and through the pivot at its lower end to the other side of the bracket and following the second bar 9 to the pivot at its upper end, 95 and so on following a set of said bars 9 from end to end of the bracket and passing from side to side thereof, and it then passes into the goose neck 15 and to the lamp socket 18 secured to the end thereof. If, however, 100 solid pivots are used, the said cord follows the same course but is kept on one side thereof and is secured at the pivots by any suitable means. A suitable wall plug 19 may be placed near the plate 1, the cord 17 leading 105 therefrom as above described.

Having described our invention, what we claim is:

In an electric light bracket, the combination with a wall plate; of a pair of vertical 110 pintles secured thereto and lying in the same axis; a pair of hinge strips bent around said

pintles; slotted links pivotally secured to each of said hinge strips and crossing each other; a friction clamp passing through the slots of said links and holding them in movable adjusted relation to each other at their crossing point; sets of crossed equal bars, each pivoted at their crossing points, and at their ends, to form an extensible bracket and pivoted to the ends of said slotted links; 10 a pair of short bars pivoted together at one end and to the end bars of the bracket at the other end to form the end of said bracket; a

goose neck adjustably pivoted to the end of said short bars; an electric lamp socket mounted on said goose neck; and an electric 15 conductor following one set of said crossed bars of the bracket and connected to said lamp socket.

ALBERT F. ANDERSON.
CHARLES W. ARMSTRONG.
